DRIVING MECHANISM FOR TWISTER TUBE
TYPE OF SPINNING FRAMESJohn A. Kooistra, North Andover, Mass., assignor
to Davis & Furber Machine Company, North
Andover, Mass., a corporation of Massachusetts

Application April 26, 1949, Serial No. 89,631

2 Claims. (Cl. 57—93)

1

This invention relates to the driving mechanism for the spindles and the twister tubes in a twister tube type of spinning frame such as extensively employed for spinning wool and other long fibre.

The object of the invention is to provide a simple and efficient mechanism by means of which the direction of rotation of the spindles may be reversed to change from that required to give a right hand twist to the yarn to that required to give a left hand twist, or vice versa, without changing or affecting the direction of rotation of the twister tubes and by means of which the speed of rotation of the spindles and the speed of rotation of the twister tubes may each be controlled or adjusted independently of the other.

The invention therefore enables, for example, not only the direction of rotation of the spindles readily to be changed whenever desired without changing the direction of rotation of the twister tubes but also the speed of rotation of the spindles to be changed as desired without affecting the speed of rotation of the twister tubes.

The twister tube type of spinning frame is well known and familiar to those skilled in the art and hence no illustration or description is necessary beyond that required for a disclosure of a preferred form of the driving mechanism to which this invention relates. Examples of one suitable type of twister tube spinning frames are disclosed in Patents Nos. 1,820,310, issued August 25, 1931, and 1,973,348, issued September 11, 1934.

In the construction illustrated:

Fig. 1 is a top plan view illustrating an ordinary arrangement of belts for driving the twister tubes;

Fig. 2 is an end elevation of the spinning frame with the end portion of the main frame partially broken away and showing the mechanism arranged for rotating the spindles in one direction; and,

Fig. 3 is a view similar to Fig. 2 showing the same mechanism for rotating the spindles in the opposite direction.

The main elements of the spinning frame are supported in a main frame comprising end sections 1. The twister tubes 2 are suitably mounted on, and extend in two rows, one at each side of, the upper portion of the main frame, and each twister tube is provided with a pulley 3. Rotation is imparted to the two rows of twister tubes by belts 4 engaging the pulleys 3 and driven from a rotating cylinder 5 extending between the end frames, as shown in Fig. 1.

2

The spinning mechanism is arranged with the spinning elements also extending in two rows, one at each side of the frame and beneath the twister tubes. In the form illustrated, which is of the ring type, the rings 6 are mounted on fixed ring frames 7 while the spindles 8 are mounted in a spindle frame 9 given the usual vertical reciprocating movement to effect the winding of the yarn on the bobbins. Each spindle is provided with a usual pulley or whirl 10 and the spindles are driven by belts 11 from a cylinder 12. Usually the belts for driving the spindles are arranged so that each belt drives a plurality of spindles at both sides of the frame as shown, for example, in the said Patent No. 1,820,310.

Each yarn 13 being spun leads down through the twister tubes where the required false twist is imparted and from thence down to the spinning elements.

20 The spinning frame is operated from any suitable source of power and for that purpose an electric motor 14 is preferably employed and located adjacent the end frame 1. Either by such a motor or by any suitable means a main shaft 15 is driven and constitutes the main driving element for both the twister tubes and the spindles. As illustrated this shaft is located above the motor 14 and driven by a belt 16 extending around a pulley 17 on the motor and a pulley 18 on the main shaft 15. One important feature 30 of the invention is that the twister tubes on the one hand and the spindles on the other hand are driven independently from this main driving shaft and this is important in enabling the results secured by the present invention to be effected.

The driving arrangement by means of which the rotation of the twister tubes and of the spindles is effected to secure the preferred embodiment of the invention as illustrated comprises a series of sprockets and cooperating chains, but it is to be understood that these terms as used herein and in the claims apply to any equivalent means such as pulleys and belts and the illustration is therefore of a diagrammatic nature.

45 The means here employed for driving the twister tubes from the main or driven shaft 15, in the preferred form illustrated, are as follows: A sprocket 19 on the main frame, and preferably 50 directly on the main shaft 15, is driven by the main shaft and through a chain 20 drives a sprocket 21 on a shaft 22 on the main frame. This shaft 22 carries a sprocket 23 which drives, by means of a chain 24, a sprocket 25 connected 55 to and driving the cylinder 5. Adjustably

mounted on the main frame is a take-up idler sprocket 26 engaging the chain 24 to maintain proper tension therein. Any of the sprockets 19, 21, 23, and 25 may be removed and replaced with others of different diameter to cause any required speed to be imparted from the driven shaft 15 to the cylinder 5 and consequently to the twister tubes. Such changes, however, will usually be made by changing the sprockets 23 and 25 and in Fig. 3, as an illustration, the sprocket 25 has been replaced by a larger sprocket 250 and the take-up idler sprocket 26 adjusted to compensate for the slackening of the chain.

This enables the same chain 24 to be employed when these sprockets are changed. It will be noted, however, that the drive from the main driven shaft 15 through to the twister tubes is entirely independent of any changes made in the drive from this main shaft to the spindles.

The arrangement for driving the spindles is effected by driving the spindle cylinder 12 directly from the main shaft 15 and also includes a series of sprockets and a sprocket chain. In the construction illustrated a sprocket 27 is driven directly by the main shaft 15 and preferably is mounted directly on that shaft. A sprocket 28 is connected to and so as to drive the spindle cylinder 12. An idler shaft 29 with an idler sprocket 30 thereon are located at the opposite side of the sprocket 28 from the sprocket 27 and a chain 31 is employed together with a take-up idler sprocket 32 adjustably mounted on the main frame.

When the spindle cylinder 12 is to be rotated, as indicated by the arrow thereon in Fig. 2 so as to drive the spindles in one direction, the chain 31 is placed, as illustrated in Fig. 2, around the sprocket 27, around the idler sprocket 30, around the take-up idler sprocket 32, and over the sprocket 28. Then with the main driven shaft 19 rotating in the direction indicated by the arrow 33 the spindle cylinder 12 will be driven in the direction indicated by the arrow.

When now it is desired to reverse the rotation of the spindle cylinder 12 the parts are arranged, as shown in Fig. 3, that is, the idler sprocket 30 is removed from its shaft 29 and the chain 31 is placed around the sprockets 27, 28, and the take-up idler sprocket 32, with the result that while the main shaft 15 is still rotating in the same direction as before, as indicated by the arrow 33, the spindle cylinder 12 now rotates in the opposite direction as indicated by the arrow thereon in Fig. 3.

Also the sprockets 27 and 28 may be removed and replaced with others of different diameter as required at any time for changing the speed of rotation of the spindle cylinder 12 and the chain 31 taken up by adjusting the take-up idler 32.

Consequently not only the change in the direc-

tion of rotation, but change in the speed of rotation of the spindles may readily be effected as required entirely independently of the twister tubes and the drive thereto.

Having thus described the invention, what is claimed as new, and desired to be secured by Letters Patent, is:

1. In a twister tube type of spinning frame having a main frame, a driven shaft, means for driving the twister tubes from the driven shaft, a cylinder for driving the spindles, a sprocket on the driven shaft, and a second sprocket for driving the cylinder, the combination of an idler shaft and a third sprocket thereon located at the opposite side of the second sprocket from the first sprocket, a take-up idler sprocket located below the first and second sprockets and adjustably mounted on the main frame, and a chain acting, when placed around the first, third and take-up idler sprockets and over the second sprocket, to drive the cylinder in one direction and, when placed around the first, second and take-up idler sprockets, to drive the cylinder in the opposite direction, whereby the direction of rotation of the spindles may be reversed without changing the direction of rotation of the tubes and the speed of each controlled independently of the other.

2. In a twister tube type of spinning frame having a main frame, a driven shaft, a sprocket on the main frame driven by the main shaft, a cylinder for driving the tubes, a second sprocket for driving the cylinder, a take-up idler sprocket adjustably mounted on the main frame and a chain extending around the said three sprockets, a cylinder for driving the spindles, a fourth sprocket on the driven shaft, and a fifth sprocket for driving the spindle cylinder, the combination of an idler shaft and a sixth sprocket thereon located at the opposite side of the fifth sprocket from the fourth sprocket, a take-up idler sprocket located below the fourth and fifth sprockets and adjustably mounted on the main frame, and a chain acting, when placed around the fourth, sixth and latter take-up idler sprockets and over the fifth sprocket, to drive the spindle cylinder in one direction and when placed around the fourth, fifth and said latter take-up idler sprockets, to drive the cylinder in the opposite direction, whereby either or both the driven and driving sprockets for either cylinder may be changed independently of those for the other cylinder thus to adjust independently the speeds of the tubes and spindles and whereby the direction of rotation of the spindle cylinder may be reversed without changing the direction of rotation of the tube cylinder.

JOHN A. KOOISTRA.
